Primary Examiner — Marianne Pandozzi*Assistant Examiner* — Jae Liang(74) *Attorney, Agent, or Firm* — Hodgson Russ LLP(57) **CLAIM**

The ornamental design for beverageware, as shown and described.

DESCRIPTION

FIG. 1 is an environmental front perspective view of a beverageware showing my new design;

FIG. 2 is a front view thereof; the rear view being a mirror image thereof;

FIG. 3 is a right side view thereof; the left side view being a mirror image thereof;

FIG. 4 is a top view thereof; and,

FIG. 5 is a bottom view thereof.

The broken lines illustrate unclaimed portions of the beverageware or environmental features that form no part of the claimed design.

1 Claim, 4 Drawing Sheets(56)
